UNITED STATES PATENT OFFICE.

WILLIAM J. CAMPBELL, OF INDIANAPOLIS, INDIANA, ASSIGNOR TO AMERICAN SLICING MACHINE CO., OF CHICAGO, ILLINOIS, A CORPORATION OF NEW YORK.

SLICING MACHINE.

Application filed April 15, 1922. Serial No. 552,983.

To all whom it may concern:

Be it known that I, WILLIAM J. CAMPBELL, a citizen of the United States, residing at Indianapolis, in the county of Marion and State of Indiana, have invented a certain new and useful Improvement in Slicing Machines, of which the following is a specification.

My invention relates to a slicing machine, and particularly to a machine which is adapted for both manual and power operation. It has for object to provide a flexible, simple and efficient power plant for driving a slicing machine which permits manual and electric power to be used at will. Another object is to provide driving means in which all rattle and play shall be efficiently and completely eliminated. Another object is to provide a machine which may be mechanically driven at varying rates of speed. Other objects will appear from time to time in the course of the specification.

I illustrate my invention more or less diagrammatically in the accompanying drawings, wherein—

Fig. 1 is a side elevation of the frame showing a slicing machine mounted thereon;

Fig. 2 is a view of the driving mechanism in the same direction as Fig. 1, with the supporting frame in section;

Fig. 3 is a section on the line 3—3 of Fig. 2;

Fig. 4 is an inverted plan view of the supporting base frame;

Fig. 5 is a detailed section along the line 5—5 of Fig. 3; and

Fig. 6 is a detail showing a modified form of motor suspension.

Like parts are indicated by like characters throughout the drawings.

A is a tapered wall pedestal having the bottom support A¹ and the removable side panels A². Mounted in the pedestal are opposed bearings A³ A⁴ and A⁵ A⁶, each bearing being provided with a removable cap A⁷. Mounted on these bearings are shafts A⁸ A⁹.

Keyed to the shaft A⁸ is the pulley B, about which travels the belt B¹, which is driven by the pulley B² on the motor B³.

The motor is mounted on the support C, which is provided with the cross-member C¹ pivoted on the base to the supports C² C³. The opposite end of the support C is perforated

to receive the bolts C⁴ C⁵, which are axially movable in the lugs C⁶ inwardly projecting from the pedestal. Nuts C⁶ C⁷ engage either side of the lug C⁶ and rotation of the screw C⁸ serves to lift or depress the support C and thus vary the position of the motor in relation to the pulley B. A cross element C⁹ removably bolted to the pedestal, as at C¹⁰ C¹¹, serves to limit the movement of the base C in a downward direction.

Keyed to the shaft A⁹ are the pulleys D¹, one being of considerably larger diameter than the other. Belts D² D³ furnish a driving connection between these pulleys with the pulleys D⁴ D⁵ rotatably mounted on the shaft A⁹. These pulleys are provided with any suitable clutch elements, for example the toothed surfaces D⁶ D⁷, which are adapted to be engaged by similar opposed surfaces on the clutch element D⁸, which is feathered to the shaft A⁹ and controlled by any suitable means, for example the jaw D¹⁰, controlled in any suitable manner by the external lever D¹¹.

Tension in the belts D² D³ is maintained by the action of the automatic tension levers E E¹, each of which is provided with a belt engaging roller E², the lower end of each lever being operated on by a spiral spring E³ attached as at E⁴ to the side of the pedestal opposite to the tension lever. The upper end of the levers are pivotally mounted, for example on the rod E⁵.

Keyed to the shaft A⁹ is a sprocket element F adapted to drive the sprocket chain F¹, which in turn drives the sprocket member F² on the slicing machine shaft F³. The slicing machine proper is not concerned in the present invention and will not be further described.

The top of the pedestal is provided with flanges G, which are each perforated to receive a screw-threaded bolt G¹, which has a stop G² and an upper cylindrical portion G³ adapted to engage perforations in the bottom of the slicing machine. These bolts obviously are separately adjustable and may be raised or lowered by rotation of the nut G⁴, which is sunk beneath the surface of the flange G.

In Fig. 6 I show a variant form of motor support, in which the motor B³ is mounted on the base element C and is drawn down against the belt B¹ by its own weight and by the tension of the spiral spring X.

It will be understood that while I have shown and described an operative device, still many changes might be made in the number, size, shape and relation of parts 5 without departing from the spirit of my invention. I wish, therefore, that my drawings be regarded as largely diagrammatic.

The use and operation of my invention are as follows:

- 10 I provide what amounts to a power plant for slicing machines, which is inclosed within a pedestal and driven, when desired, by a motor mounted within the pedestal. In order to reduce rattling and play to a minimum, the motor is connected with the pulley by a belt. Because of the size of the pulley and the short distance which separates it from the motor, a separate tension member on the belt is impractical and, if used, would 15 make a terrific din. I therefore provide for tension on the belt by mounting the motor on a hinged base and by positively adjusting the position of the base and motor in relation to the pulley by rotating the screw C^3 , as 20 shown in Fig. 3. The tension may thus be initially set and may, of course, be adjusted from time to time as the operation of the machine warrants. I may also dispense with the positive connection and merely suspend 25 the motor within the belt B^1 , further adding to the tension by the spiral spring X , but the first mentioned form seems at present preferable.

- The transverse member C^6 serves as a stop 30 to limit the motion of the support C , and even if the belt comes off and the screw C^3 is rotated to lower the base as far as it can be lowered, the motor cannot drop through the bottom of the machine. This is particularly important in connection with the 35 form shown in Fig. 6. This is also particularly useful as permitting a ready removal of the motor in case cleaning or repair is necessary, or in case the user wishes 40 to substitute another motor or type of motor. The member C^6 is simply removed and the pedestal may then be tilted over on its side, leaving the support C with the motor thereon lying in freely available position.

- 45 The pulley B positively drives the shaft A^8 , and rotating with the shaft are two pulleys of varying size, the smaller one, of course, giving a slower movement to the belt driven by it than the larger one. These two 50 pulleys and the belts which they drive in turn drive two pulleys of equal size rotatably mounted on the upper shaft A^9 , each of the pulleys being constantly driven when the shaft A^8 is in motion. I provide a clutch element feathered to the shaft between the two pulleys, which may be alternately thrown 55 into operative engagement with the one or the other, depending on whether a high or low speed drive is desired. When it is in 60 neutral, both pulleys simply spin on the 65

shaft A^9 , which then lies idle. When it is thrown into engagement with the pulley driven by the low speed pulley, the shaft A^9 is actuated at a low speed and transmits this speed through the sprocket chain F^1 to the slicing machine; when the clutch is thrown into operative engagement with the other pulley, the higher speed is transmitted. When the clutch is in idle, the manual crank 70 may be rotated, which operates the machine and, of course, drives the shaft A^9 without giving any rotation to the two pulleys loosely mounted thereon. The simple external control lever provides for varying the speed or throwing the clutch out. 75

80 Fig. 1 shows the general disposition of the device, but since the details of the slicing machine proper do not form part of the present invention it is not described, beyond stating that it consists of a rotary knife, a support for gripping the material to be cut, means for feeding this support forward toward the knife, and means for reciprocating it back and forth across the face of the knife. The bottom of the slicing machine is provided with holes which fit the studs G^8 at the top of the bolt G' . An adjustment of these bolts permits a leveling or centering of the slicing machine on the base, to correct for irregularities of the base, or rather of the 85 floor on which it rests. 90

95 An even more important function of these studs is the adjustment of the tension of the flexible chain F' which provides the driving connection between the power plant in the base and the shaft F^3 of the machine. If the chain is loose and tends to rattle, the studs may be lifted to raise the slicing machine bodily on the base and thus to correct the tension of the chain by increasing the distance 100 between the sprockets. 105

I claim:

110 1. A combined slicing machine support and power driving unit, comprising a pedestal casing, a motor mounted within said casing, and a variable speed connection adapted to connect said motor with the driving shaft of a slicing machine supported upon the casing.

115 2. A combined slicing machine support and power driving unit, comprising a pedestal casing, a motor mounted within said casing, and a variable speed connection adapted to connect said motor with the driving shaft of a slicing machine supported upon the casing, and means for adjusting the tension of said connection.

120 125 3. A combined slicing machine support and power driving unit, comprising a pedestal casing, a motor mounted within said casing, and a variable speed connection adapted to connect said motor with the driving shaft of a slicing machine supported upon the casing, and means for controlling the tension of said connection by varying the 130

distance between the support and the slicing machine.

4. A combined slicing machine support and power driving unit, comprising a pedestal casing, a motor mounted within said casing, and a variable speed connection adapted to connect said motor with the driving shaft of a slicing machine supported upon the casing, and means for controlling the tension of said connection by varying the distance between the support and the slicing machine, comprising a plurality of slicing machine supporting set screws upon said base.

15 5. A combined slicing machine support and power driving unit, comprising a pedestal casing, a motor mounted within said casing, and a variable speed connection adapted to connect said motor with the driving shaft of a slicing machine supported upon the casing, and means for controlling the tension of said connection by varying the distance between the support and the slicing machine, comprising a plurality of slicing machine supporting elements vertically adjustable in relation to the top of said base.

6. A combined slicing machine support and power driving unit, comprising a pedestal casing, a motor mounted within and upon said casing, a plurality of shafts journaled in said casing, a driving connection between one of said shafts and the motor, a variable speed connection between the first of said shafts and the second, and a driving connection adapted to connect said second shaft with the drive shaft of a slicing machine mounted upon said casing.

7. A combined slicing machine support and power driving unit, comprising a pedestal casing, a motor mounted within and upon said casing, a plurality of shafts journaled in said casing, a driving connection between one of said shafts and the motor, a variable speed connection between the first of said shafts and the second, and a driving connection adapted to connect said second shaft with the drive shaft of a slicing machine mounted upon said casing, a control member for said variable speed connection, said pedestal being slotted to permit the outer end of said member to project.

8. In a slicing machine supporting base, a driving shaft mounted in said base, a flexible driving connection adapted to connect it with the drive shaft of a slicing machine supported upon said base, and means for adjusting the tension of said connection, comprising means for vertically adjusting the slicing machine upon the supporting base.

9. In a slicing machine supporting base, a driving shaft mounted in said base, a flexible driving connection adapted to con-

nect it with the drive shaft of a slicing machine supported upon said base, and means for adjusting the tension of said connection, comprising a plurality of vertically adjustable slicing machine supporting ele- 70

10. In a slicing machine support, a pedestal casing adapted to receive a slicing machine upon the top thereof, driving means within said casing, and a flexible driving 75 connection passing through the top of said casing and adapted to be connected to and to drive said slicing machine, and means for adjusting the slicing machine upon the casing and for adjusting said flexible connection comprising a plurality of separately adjustable supporting elements upon the top of the casing.

11. A slicing machine driving unit comprising a pedestal casing adapted to receive a 80 slicing machine on the top thereof, a motor pivoted to the interior of said casing, a plurality of shafts journaled in said casing, a flexible driving connection between one of said shafts and the motor, and means for 85 adjusting the tension thereof, comprising means for swinging the motor about its pivot, a driving connection between said shafts, and a driving connection between one of said shafts and the slicing machine. 90

12. A combined slicing machine support and power driving unit, comprising a pedestal casing, a motor mounted within and upon said casing, a plurality of shafts journaled in said casing, a driving connection between 100 one of said shafts and the motor, a variable speed connection between the first of said shafts and the second, and a driving connection adapted to connect said second shaft with the drive shaft of a slicing machine 105 mounted upon said casing.

13. A combined slicing machine support and power driving unit, comprising a pedestal casing, a motor mounted within and upon said casing, a plurality of shafts journaled in said casing, a driving connection between one of said shafts and the motor, a variable speed connection between the first of said shafts and the second, a driving connection adapted to connect said second shaft 110 with the drive shaft of a slicing machine mounted upon said casing, and a control member for said variable speed connection, said pedestal being slotted to permit the outer end of said member to project. 115

14. In a slicing machine, a hand operated driving shaft, a motor, a motor driven shaft, a flexible connection between said shaft and the hand operated shaft, and means for positively interrupting the connection between the motor and the motor driven shaft during hand rotation of the slicing machine. 125

15. In a slicing machine, a hand operated driving shaft, a motor, a motor driven shaft, 130

a flexible connection between said shaft and the hand operated shaft, and means for interrupting the connection between the motor and the motor driven shaft during hand rotation of the slicing machine, the connection between the hand operated shaft and the motor driven shaft being constant.

16. In an open bottomed supporting pedestal for slicing machines, a motor, a driven shaft and a flexible connection between said motor and said shaft, a motor supporting platform, pivoted within and adjacent the bottom of said pedestal, means independent of the connections between the motor and the shaft, for normally preventing the escape of said platform through the bottom of said pedestal, and means for adjusting said platform about its pivot, the platform being positioned and proportioned to swing through the open bottom of the pedestal when the pedestal is tilted.

17. In an open bottomed, supporting pedestal for slicing machines, a motor, a driven shaft, and a flexible connection between said

motor and shaft, a motor supporting platform pivoted beneath said shaft, upon a horizontal axis, and adapted to lie normally in a substantially horizontal plane, means for rotating said motor and platform about said pivot, said platform being positioned and proportioned to swing through the open bottom of the pedestal, when the pedestal is tilted.

18. In a combined supporting pedestal and power plant for slicing machines, a motor, a driven shaft, a pulley upon said shaft, a belt connecting said pulley with said motor, the size of said pulley and its distance from the motor being such that the reaches of said belt are in sharply inclined relation to each other, and means for tightening said belt, comprising means for moving said motor in relation to said pulley.

Signed at Indianapolis, county of Marion and State of Indiana, this 7th day of April, 1922.

WILLIAM J. CAMPBELL.
